ALUMINUM DIE-CASTING MACHINE

William B. Beuscher, Kansas City, Mo., assignor
to Rupert Diecasting Company, Kansas City,
Mo., a corporation of Missouri

Application May 23, 1949, Serial No. 94,808

4 Claims. (Cl. 22—68)

1

This invention relates to an aluminum diecasting machine having a shot cylinder assembly.

The principal object of the present invention is the provision of an aluminum diecasting machine having a fast moving plunger with an extra thrust at the latter portion of the strokes which is accomplished without the use of excessive line pressure or expensive pump equipment.

Another object is to provide means to unload or relieve extra thrust to said plunger before opening the dies of said machine.

A further object is to provide means to regulate the thrust to said plunger to any desired degree.

Other objects are economy of construction, ease and efficiency of operation and adaptability for use with diecasting machines for the casting of materials of various compositions.

With these objects in view as well as other objects which will appear in the course of the specification, reference will be had to the drawing wherein the single drawing is a diagrammatic view of an aluminum diecasting machine, which is better and more completely shown in my co-pending application, Serial No. 700,413, filed October 1, 1946, now matured into Patent No. 2,492,289, and also in the drawing is a diagrammatic showing of the associated hydraulic equipment embodying the present invention.

In the drawing like reference characters refer to similar parts and the numeral 14 designates a machine base provided adjacent its one end with a vertically disposed fixed platen 16 to which the stationary part 18 of the die or mold 20 is rigidly attached.

Adjustably mounted on the other end of base 14 is an end plate 22. Parallel tie bars 24 tie the fixed platen 16 and the end plate 22 together. The movable part 34 of the die or mold is mounted on a movable platen 36 which is slidably mounted on the parallel tie bars 24.

To effect the desired opening and closing of the die members, a reciprocating movement is imparted to the movable platen 36 by a toggle linkage comprising side bars 38, toggle links 40, cross head 42, and a piston rod 44. Toggle links 40 are respectively pivotally connected to side bars 38 by means of pin 39 and to cross head 42 by a pin 41, and side bars 38 are pivoted to platen 36 by pins 43. A cylinder 46 is provided with means to receive fluid under pressure, which serves to move the piston 47 to drive piston rod 44.

The shot cylinder 50 and the booster cylinder 52 are important elements which will be further explained in their operations to deliver molten metal into the die.

2

Shot cylinder 50 is rigidly fixed in relation to base 14, and is provided with a piston 53 to which a piston rod 54 is mounted for reciprocation by the action of fluid pressure alternately fed to opposite ends of said cylinder. Piston rod 54 carried by piston 53 extends through the inner end of cylinder 50. A plunger 58 mounted on the end of piston rod 54 operatively fits in bore 60 leading to the mold cavity, and when the piston 52 is at its outer end of travel the plunger 58 will be moved to uncover metal inlet port 64. With the plunger in this position, molten metal will flow into bore 60 so that with the next stroke of the piston 53 a charge of metal will be forced into the die mold. Booster cylinder 52 mounted on cylinder 50 is provided with a piston 66 of relatively small diameter carrying a piston rod 68 which extends into shot cylinder 50 ahead of piston 53.

At the lower left hand corner of the sheet of drawing is shown an open tank 70, pumps 72 and 74 which are driven by a motor 76. At the extreme right of the drawing is an accumulator 78 to store up a large volume of oil or other hydraulic fluid which is pumped in through pipe 80 by pump 72 to the bottom of the accumulator against a predetermined volume of nitrogen or some other inert gas contained in said accumulator. The pressure in the accumulator will rise to the normal delivery pressure of the pump and will have instant delivery to the shot cylinder 50 when the control valve is opened. Pipe 80 is provided with a check valve 82 to prevent reverse flow, and with a shut-off valve 84. Throughout the drawing it will be noted that the operative pressure pipes are indicated by double lines, while the control pressure pipes are indicated by single lines.

A pilot valve 86 is connected to pipe 80 by pipes 88 and 90, and an exhaust line 92 returns from 40 said pilot valve to tank 70. Pipe 94 interconnects valve 86 with shot cylinder 50 ahead of piston 53 through a throttling valve 96 and spring loaded check valve 98. Pipe 100 connects valve 86 with cylinder 50 behind piston 53. Pilot valve 86 is controlled by a sliding spool 102. It will be noted that when said spool is in its left position as shown in the drawing, fluid from pressure pipe 80 will pass through pipe 88, pilot valve 86, pipe 94, throttling valve 96, and check valve 98 to shot cylinder 50, forcing piston 53 to the left. At the same time, fluid contained in cylinder 50 behind piston 53 will be exhausted through pipe 100, valve 86, and pipe 92 to tank 70. When spool 102 is moved to the right, fluid will pass 50 through pipe 90, pilot valve 86 and pipe 100 to

cylinder 50 behind piston 53, forcing said piston to the right, and fluid ahead of said piston will be exhausted through pipe 94, valve 86, and pipe 92 to tank 70, check valve 98 being opened to permit reverse flow by means hereinafter described.

The opposite ends of spool 102 of pilot valve 86 are formed to present pistons 104 and 106 respectively, disposed in cavities in the valve body and adapted to be acted upon by fluid under pressure to operate the spool. Fluid for this purpose is furnished by control valve 108, which is of the rotary plug type controlled manually by handle 110. When said handle is moved clockwise as shown, fluid under pressure from pump 72 passes through pipes 112 and 114, through control valve 108 to pipe 116, and thence to pilot valve 86 to act on piston 104 to move spool 102 to the left. At the same time, fluid exhausted by piston 106 passes through pipes 118 and 120, control valve 108, pipe 122, and pipe 124 to tank 70. When handle 110 is moved counter-clockwise, fluid entering control valve 108 is connected with pipe 120, and thence through pipe 118 to act on piston 106 to move spool 102 to the right. Fluid exhausted at this time by piston 104 flows through pipe 116, control valve 108, and tank return pipes 122 and 124. Pipe 120 is also connected with spring loaded check valve 98, and is adapted to supply fluid for operating a piston 126 adapted to open said valve.

Pipe 94 leading from pilot valve 86 to shot cylinder 50 is also connected with booster cylinder 52 ahead of piston 66 by means of pipe 128, in which are inserted throttling valve 130, and adjustable pressure regulator valve 132. A cross connecting pipe 134 interconnects pipes 94 and 128, and a valve 136 is inserted in said by-pass pipe. Said valve is of the sliding piston type, and is spring loaded to be held normally closed. Fluid under pressure from pump 72 flows through pipe 112, push button valve 138, and pipe 140 to relief valve 136, where it acts on piston 142 to open said valve. Valve 138 is spring loaded to normally maintain connection between pipe 140 and tank return line 124. Only when said valve is depressed manually is pipe 140 connected with pressure line 112.

Die operating piston 47 is controlled by a pilot valve 144 and a control valve 146 similar to pilot valve 86 and control valve 108 which operate the shot and booster pistons. Pipes 148 and 150 interconnect pump 74 with pilot valve 144, and exhaust pipe 152 returns from said valve to tank 70. Pipes 154 and 156 interconnect said pilot valve with cylinder 46 respectively in front of and behind piston 47. Pilot valve 144 is controlled by a sliding spool 158. When said spool is at the right end of its travel as shown in the drawing, fluid under pressure from pump 74 flows through pipe 148, valve 144, and pipe 154 to cylinder 46, forcing piston 47 to the right, and fluid behind said piston is exhausted through pipe 156, valve 144, and pipe 152 to tank 70. When spool 158 is at the left end of its travel, fluid from pump 74 flows through pipe 150, valve 144, and pipe 156 to cylinder 46 to force piston 47 to the left, and fluid in front of said piston is exhausted through pipe 154, valve 144, and pipe 152. The opposite ends of spool 158 are formed to present pistons 160 and 162 respectively for moving said spool. Fluid for actuating said pistons is furnished by control valve 146 similar to valve 108 and having a manual operating handle 164. When said handle is moved clockwise as shown in the drawing, fluid from pump 74 flows through

pipes 148 and 166 to valve 146, and is connected thereby with pipe 168, which delivers fluid to the left end of pilot valve 144 to actuate piston 160. When handle 164 is moved counter-clockwise, fluid entering valve 146 through pipe 166 is connected with pipe 170, which delivers fluid to the right end of pilot valve 144 to actuate piston 162. Fluid exhausted by pistons 160 and 162 is returned from valve 146 to tank return line 124 by pipe 172.

The operation of the diecasting machine is substantially as follows. With the machine open, with both the die operating piston 47 and shot piston 53 retracted, the operator first moves handle 164 of control valve 146 clockwise, as shown in the drawing. Fluid under pressure then flows from pump 74 through pipes 148 and 166, valve 146, and pipe 168 to pilot valve 144, actuating piston 160 to move valve spool 158 to the right. Fluid then flows through pipe 148, pilot valve 144, and pipe 154 to cylinder 46 ahead of piston 47, forcing said piston to the right to move the movable platen 36 to the right to bring the die members 34 and 18 together. When the die is closed, side bars 38 of the toggle mechanism are pivoted outwardly by toggle links 40 to engage shoes 45 to lock the dies in the closed position. A suitable charge of molten metal is then introduced into bore 60 of fixed platen 16 ahead of plunger 58 through port 64, by any suitable means not shown. The operator then moves handle 110 of control valve 108 clockwise, as shown in the drawing, thereby permitting fluid under pressure to flow from pump 72 through pipes 112 and 114, valve 108, pipe 116 to pilot valve 86, where it actuates piston 104 to move valve spool 102 to the left. Fluid from pump 72 then flows through pipe 80, pipe 88, valve 86, pipe 94, throttling valve 96, and check valve 98 to shot cylinder 50, forcing piston 53 to the left, whereby plunger 58 forces the charge of molten metal into the die cavity. At the same time, fluid pressure passes through pipes 128, throttling valve 130, and regulating valve 132 to booster cylinder 52, advancing booster piston 66. Thus the shot and booster pistons move simultaneously, but throttling valve 130 restricts fluid flow to the booster cylinder so that the shot piston 53 completes its stroke before booster piston 66 completes its stroke.

When the fluid pressure in shot cylinder 50 reaches full pump pressure, fluid flow through pipe 94 ceases and check valve 98 closes automatically, and piston 53 stops movement because the mold cavity has become filled with molten metal. However, fluid continues to flow through pipe 128, and booster piston 66 continues to move forwardly, whereby piston rod 68 displaces fluid in cylinder 50. The pressure in cylinder 50 is thereby increased to a level equal to the pressure introduced into booster cylinder 52 multiplied by the ratio of the areas of piston 66 and piston rod 68. The increased booster pressure in shot cylinder 50 produces additional forward movement of shot piston 53 and plunger 58, and thereby functions to feed additional metal into the die mold, to feed the shrink of the casting, reduce the porosity of the casting, and provide a smoother surface on the casting. The speed of the stroke of shot piston 53 may be regulated by throttling valve 96, and throttling valve 130 is adjusted to provide the speed differential in the strokes of pistons 53 and 66 as previously described. The magnitude of the pressure supplied by the booster piston may be controlled by

regulating valve 132, which closes automatically whenever the fluid pressure supplied to cylinder 52 reaches a predetermined level.

It will be noted that the entire booster pressure is transmitted through plunger 58, the casting, and movable platen 36 to the die-operating toggle mechanism. If said toggle mechanism were opened while the extreme booster pressure was being applied, it would be subjected to violent shocks which would shorten the life of the machine. Thus, as the first step in opening the machine, the operator manually depresses push-button valve 138 to interconnect pump pressure line 112 with pipe 140, whereby fluid is conducted to relief valve 136 to open said valve by actuating piston 142. The opening of said valve by-passes fluid from shot cylinder 50 to pipe 128, which is at pump pressure. The pressure in cylinder 50 is thereby reduced to pump pressure, and the dies may be opened under this load without damage to the toggle mechanism. While holding valve 138 depressed, the operator turns handle 164 of control valve 146 counter-clockwise, thus admitting fluid under pressure to pipe 170 to actuate piston 162 to move spool 158 of pilot valve 144 to the left. Fluid under pressure from pump 74 thereupon flows through pipe 150, pilot valve 144, and pipe 156 to cylinder 46 behind piston 47, forcing said piston to the left to open the die members. As the die members separate, the pressure in shot cylinder 50 drops, check valve 98 opens, and additional fluid flows into said cylinder to force piston 53 still farther to the left. Plunger 58 is thereby advanced to eject the residual slug of metal from bore 60. When said slug has been ejected, the operator moves handle 110 of control valve 108 counterclockwise, thereby supplying fluid under pressure to pipes 120 and 118, whereby check valve 98 is opened and spool 102 of pilot valve 86 is moved to the right. Fluid under pressure from pipe 80 then flows through pipe 90, pilot valve 86, and pipe 100 to cylinder 50 behind piston 53, forcing said piston to the right. Piston 58 strikes the inner end of piston rod 68 and forces piston 66 to its retracted position. Fluid ahead of piston 53 is exhausted through pipe 94, open check valve 98, valve 96, pilot valve 86, and pipe 92 to tank 70. Fluid ahead of booster piston 66 is exhausted through pipe 128, regulating valve 132, and valve 130 to pipe 94. The machine is then ready for repetitions of the cycle as desired.

Thus it is apparent that a die-casting machine having several advantages has been produced. The injection pressure builds up smoothly and without steps from zero to many times pump pressure.

The magnitude and speed of thrust are readily adjustable. Expensive pumping equipment and excessive line pressures are not necessary to produce to booster pressure. Check valve 98 and relief valve 136 are the only valves subjected to the multiplied pressure and it is contemplated that these valves be built directly into the thickened walls of shot cylinder 50. The die-operating toggle mechanism is protected from damage by excessive pressure. It is obvious that control valve 146 and push-button valve 138 could be so related, either mechanically or hydraulically, that the dies could not be opened so long as full booster pressure is being applied to the shot piston.

While I have shown a specific embodiment of my invention, it is apparent that many minor

variations could be made without departing from the spirit of the invention.

What I claim is:

1. In a die-casting machine of the class described having a die mold, a plunger adapted to inject a charge of molten metal into said mold, a hydraulically operated shot piston adapted to actuate said plunger, a hydraulic cylinder rigidly associated with said mold and in which said shot piston operates, a booster piston, a hydraulic cylinder rigidly connected to said shot cylinder and in which said booster piston operates, a rod fixed to said booster piston and extending into said shot cylinder, a pair of conduits interconnected respectively with said shot and booster cylinders, a hydraulic pump interconnected with said conduits and operable to deliver fluid under pressure simultaneously to said cylinders through said conduits, whereby said shot piston is advanced to cause said plunger to inject molten metal into said mold and whereby said booster piston is advanced to move said rod into said shot cylinder to displace fluid therein, a check valve disposed into the conduit leading to said shot cylinder and adapted to prevent reverse flow therein, and a flow restriction disposed in the conduit leading to said booster cylinder, whereby said booster piston is caused to advance more slowly than said shot piston.
2. In a die-casting machine of the class described having a die mold, a plunger adapted to inject a charge of molten metal into said mold, a hydraulically operated shot piston adapted to actuate said plunger, a hydraulic cylinder rigidly associated with said mold and in which said shot piston operates, a booster piston, a hydraulic cylinder rigidly connected to said shot cylinder and in which said booster piston operates, a rod fixed to said booster piston and extending into said shot cylinder, a pair of conduits interconnected respectively with said shot and booster cylinders, a hydraulic pump interconnected with said conduits and operable to deliver fluid under pressure simultaneously to said cylinders through said conduits, whereby said shot piston is advanced to cause said plunger to inject molten metal into said mold and whereby said booster piston is advanced to move said rod into said shot cylinder to displace fluid therein, a check valve disposed into the conduit leading to said shot cylinder and adapted to prevent reverse flow therein, and an adjustable throttling valve in each of said conduits whereby the relative rate of movement of said pistons may be adjusted.
3. In a die-casting machine of the class described having a die mold, a plunger adapted to inject a charge of molten metal into said mold, a hydraulically operated shot piston adapted to actuate said plunger, a hydraulic cylinder rigidly associated with said mold and in which said shot piston operates, a booster piston, a hydraulic cylinder rigidly connected to said shot cylinder and in which said booster piston operates, a rod fixed to said booster piston and extending into said shot cylinder, a pair of conduits interconnected respectively with said shot and booster cylinders, a hydraulic pump interconnected with said conduits and operable to deliver fluid under pressure simultaneously to said cylinders through said conduits, whereby said shot piston is advanced to cause said plunger to inject molten metal into said mold and whereby said booster piston is advanced to move said rod into said shot cylinder to displace fluid therein.

therein, a check valve disposed into the conduit leading to said shot cylinder and adapted to prevent reverse flow therein, a flow restriction in the conduit leading to said booster cylinder, whereby said booster piston is caused to advance more slowly than said shot piston, and a pressure regulating valve disposed in said last named conduit intermediate said flow restriction and said booster cylinder.

4. In a die-casting machine of the class described having a die mold, a plunger adapted to inject a charge of molten metal into said mold, a hydraulically operated shot piston adapted to actuate said plunger, a hydraulic cylinder rigidly associated with said mold and in which said shot piston operates, a booster piston, a hydraulic cylinder rigidly connected to said shot cylinder and in which said booster piston operates, a rod fixed to said booster piston and extending to said shot cylinder, a pair of conduits interconnected respectively with said shot and booster cylinders, a hydraulic pump interconnected with said conduits and operable to deliver fluid under pressure simultaneously to said cylinders through said conduits, whereby said shot piston is advanced to cause said plunger to inject molten metal into said mold and whereby said booster piston is advanced to move said rod into said shot cylinder

5 to displace fluid therein, a check valve disposed into the conduit leading to said shot cylinder and adapted to prevent reverse flow therein, a flow restriction in the conduit leading to said booster cylinder, whereby said booster piston is caused to advance more slowly than said shot piston, a by-pass conduit interconnecting said shot and booster cylinders, a normally closed valve in said by-pass conduit, and means for opening said valve.
